ADJUSTABLE GRIP BOWLING BALL

Walter J. Jankiewicz, Chesapeake, Va. (860 S. Greenbrier St. #619, Arlington, Va. 22204), and Edgar A. Norfolk, Jr., 5761 Don Drive, Norfolk, Va. 23518
Filed May 7, 1965, Ser. No. 453,918
4 Claims. (Cl. 273—63)

ABSTRACT OF THE DISCLOSURE

A bowling ball which incorporates movable devices for changing the span between the finger and thumb holes, the sizes of the finger and thumb holes, and the pitches or angle of entry of the finger and thumb holes generally. 15

The bowling ball may be so constructed that for tournament or league play the aforementioned movable devices are locked in position before, during and after delivery and cannot be removed from the bowling ball without essentially destroying the devices. For so-called "custom" fitting purposes, the movable devices will be so incorporated that they may be removed for the purpose of removably inserting finger and thumb hole inserts or balls having different hole sizes. The bowling ball may be further so constructed that by a proper choice of non-metallic composition materials of the appropriate shape and dimension it will conform exactly to American Bowling Congress (ABC) Bowling Ball Specifications for weight, size and balance requirements. When so constructed the adjustable grip bowling ball may be rolled in competition and when constructed as a fitting ball, it may be rolled experimentally on regular bowling alleys against regulation tenpins. Also, with the increased amount of family and league bowling, wherein the bowlers do not own their own bowling balls but use the balls provided by the bowling alley, the present invention provides a construction whereby each bowler not using his own bowling ball may be furnished with a ball having thumb and finger holes therein that have diameters fitting the thumb and fingers of the bowler and are properly angularly and spacially located as to give each such bowler a comfortable grip on the bowling ball. Although thumbs and fingers have been referred to theretofore, it is to be understood that they are all digits or digits of a human hand and that in the following description a thumb is as much as a digit of the hand as a finger is. It has been previously established as common knowledge to those skilled in the art that the aforementioned ability to change the span, pitch and size of the finger and thumb gripping holes is extremely desirable both for comfort, accuracy, and lift in delivering the bowling ball. It has also been considered extremely desirable to enable the bowler to determine the manner in which he or she would desire to have their own ball "custom" fitted or tailored to their particular hand or hands so that they may achieve the aforementioned comfort, accuracy and lift.

It is therefore a primary object of this invention to provide a bowling ball which by adjustment of a plurality of finger and thumb hole inserts and frusto-conical sections the bowler may achieve adjustable spans between the thumb and each of any two of the four fingers of the hand either left or right and adjustment in span between the fingers as may be considered separately or mutually desirable.

Another object of the invention is to provide different combinations of finger and thumb holes in sizes so as to conform to what may be considered the range of sizes that

2

will fit a majority of bowlers' hands both left and right as the case may be. Depending upon construction, the combinations may vary from one to one hundred eight, all of which would be possible within the same ball using a minimum of three or a maximum of nine inserts.

Still another object of the invention is to provide means whereby the pitches or angles of entry of the thumb and finger holes may be generally universally adjustable over ranges that should be adequate for the average bowler's desires.

A further object of the invention is to provide means whereby the aforementioned objects may be attainable for "custom" fitting of bowling balls so as to suit the individual bowler's comfort and accuracy requirements.

A still further object of the invention is to provide a method of construction of an adjustable grip bowling ball such that it may be accepted and manufactured as meeting the requirements of the American Bowling Congress (ABC) Bowling Ball Specifications to enable use of the ball in tournament and league play.

Other objects will become apparent as the description proceeds in connection with the accompanying drawings, wherein:

FIG. 1 is a top plan view of a bowling ball embodying the invention, and showing a spherical thumb hole insert as well as two spherical finger hole inserts, and the three frusto-conical outer surface clamping members by which they are secured to the body of the bowling ball.

FIGURE 2 is a sectional view substantially along the line 2—2 of FIGURE 1, showing a frusto-conical outer surface clamping member, two of three spherical thumb hole inserts, and a wrench for clamping or loosening the entire thumb hole assembly with respect to the bowling ball.

FIGURE 3 is an exploded view of the assembly of FIGURE 2.

FIGURE 4 is a sectional view substantially along the line 4—4 of FIGURE 1, showing a frusto-conical outer clamping member and two spherical finger hole inserts. It should be understood that the line 4—4 of FIGURE 1 is a portion of a great circle on the surface of the bowling ball, as is the line 2—2 which appears as a straight line, being perpendicular to the plane of the drawing.

FIGURES 5, 6 and 7 are three views of a finger hole insert of the assembly of FIGURE 4.

Referring to FIGURE 1, there is shown a bowling ball 10 of the type used in bowling with tenpins. Such balls are of relatively large diameter and generally have three holes therein, one for a thumb, one for a middle finger, and one for another finger, usually the ring finger, or the one next to the little finger. As explained in the foregoing portion of this disclosure, the instant invention provides for a selection of more than one hole for the thumb as well as for each of the other two fingers, and also provides for variable angular positioning of all three holes. In FIGURE 1 is shown an exposed portion of a spherical thumb hole insert or thumb ball 11 having an axial thumb hole 12 therethrough, which hole may be cylindrical or may have a slight taper from a larger to a smaller diameter from its outer to its inner end. A clamping top 13 for the thumb ball 11 is also shown, and will be described. Also shown is a middle finger ball 14 with a cylindrical or tapered hole 15 and its clamping top 16, as well as a ring finger ball 17 with a cylindrical or tapered hole 18 and its clamping top 19. As will be understood the above described relationship of the middle and ring finger balls 14 and 17 is for right hand bowlers. For left hand bowlers, the relationship would be reversed, as the middle finger hole 15 is normally larger in diameter than the ring finger hole 18.

The spherical thumb ball 11, middle finger ball 14 and ring finger ball 17 are each adjustably but rigidly secured in place by similar constructions which will be described in connection with FIGURES 1 to 3, as well as FIGURES 4 to 7 which are particularly applicable to the ring finger and ring finger balls.

Referring to FIGURES 2 and 3, the bowling ball 10 has a cavity which is indicated generally by reference numeral 23 in FIGURE 3 and is generally but not completely conical, having its largest diameter at the surface of the ball. The outermost portion of the cavity 23 has a conical wall 24 which terminates in a circular recess 25 (FIGURE 2) rectangular in cross section, in which is seated a resilient rubber O-ring gasket 26. The clamping top 13 which covers the cavity 23 so as to complete the spherical surface of the ball 10 where the cavity 23 occurs has a conical peripheral wall 27 which has a mating engagement with the conical wall 24 of the cavity and also has a flat chordal inner wall 64 (FIGURE 2) the outer periphery of which engages the top of the O-ring 26.

Below the circular recess 25 the recess 23 is in the shape of a portion of a sphere cut by two parallel planes spaced from but intersecting its outer surface. This portion of the recess is indicated by the reference numeral 29 in FIGURES 2 and 3. Inwardly from the portion 29 the recess terminates in portions, the shape of which is not important, but which in FIGURES 2 and 3 are shown as inwardly tapering frusto-conical walls 34 and 35 of differing inclination. At the inner end or root of the wall 35 a gear seat insert 36 is threaded at 37 into mating threads in the body of the bowling ball 10 and secured by a suitable cement so that it is not removable.

Journalized for rotation within the gear seat insert 36 is a gear retainer 38 having an enlarged integral cylindrical head 39 seated within a mating enlarged and shouldered recess 40 in the gear seat insert 36. A pair of washers 43 and 44 made of a frictionless material such as "Teflon" or the like above the head 39 reduce friction when the gear retainer 38 is rotated while under axial tension. A spur gear 45 having a locking function which will be described, and which may be cylindrical or slightly conical, is secured to the outer end of the gear retainer 38 as by internal threads 47 which are affixed by a suitable cement or otherwise fused to the threaded outer end of the gear retainer 38, after shaft 60 is inserted, and a pair of "Teflon" or the like washers 48 and 49 between the gear 45 and the fixed gear seat insert 36 may be used to reduce friction.

The gear retainer 38 extends only partially into the internally threaded portion of the spur gear 45, as is apparent from FIGURE 2, and a unitary rotatable assembly comprising the gear retainer 38 and the locking spur gear 45 may be rotated by a wrench 52 having a spindle 53, a handle 54, a conical spur gear 55 and a spindle 56 which is inserted into one of a circular series of spindle holes 57 in the outer surface of the gear seat insert 36. The wrench spindle 53 is inserted through the thumb hole 12 in a thumb ball 11 as best shown in FIGURE 2, and the action of the wrench 52 in tightening a thumb ball 11 between the recess in the bowling ball 10 and the clamping top 13 will now be described.

A locking shaft 60, coaxial with the gear retainer 38 has an integral enlarged inner end 61 which is threadededly received in the outer threaded portion of the internally threaded spur gear 45, which terminates in an inwardly directed shoulder 59 as shown in FIGURE 2. Its outer end 62 is threaded into a blind tapped hole 63 in the center of the thumb ball clamping top 13 and fixedly secured therein by the use of a suitable cement. As will be apparent from FIGURE 2, the turning of the wrench 52 in one direction will rotate the locking gear 45 to pull the locking shaft 60 inwardly toward the center of the bowling ball 10 together with the clamping top 13. Turning the wrench 52 in the other direction will loosen the clamping top.

The clamping top 13 has an inner planar surface 64

which is chordal to the surface of the bowling ball 10, the periphery of the surface 64 bearing against the O-ring gasket 26. The inner planar surface 64 of the clamping top is interrupted by a number of partial spherical recesses 5 corresponding to the number of spherical thumb hole inserts or thumb balls 11 that are to be secured between the clamping top 13 and the cavity (FIGURE 3) in the ball. While necessarily there must be at least one such thumb ball 11 with its thumb hole 12, the embodiment of FIGURES 2 and 3 has three such thumb balls equiangularly spaced and secured by the clamping top 13, each thumb ball having the same spherical diameter but having a thumb hole 12 of a different diameter.

In FIGURE 2 the thumb ball 11 is shown in vertical section. It is clamped between a part of the spherical portion 29 of the cavity 23 in the ball 10 and a substantially hemispherical recess 67 on the inner surface of the clamp top 13, which recess terminates in a hole 68 through the surface of the clamp top. As will be apparent from FIGURE 2, loosening of the clamp top 13 by the wrench 52 and continued rotation of the wrench will allow the clamp top to be raised above the outer surface of the ball 10 so as to clear the three thumb balls and be rotated about the axis of the locking shaft 60 and the hole 68 to rotate about 20 the same axis to position it in any location about the axis so as to position any one of the thumb balls in alignment with the hole 68. Also, while the clamp top is just loosened, any thumb ball may be moved in any direction until its thumb hole 12 is in a position that is comfortable to the bowler. Assuming that the thumb hole 12 is of the proper tapered diameter to suit the bowler and is properly positioned, it may be locked in place by pulling the clamp top 13 against its seat and securing it by means of the wrench 52.

35 After assembly it is apparent that while the clamping top may be loosened for the purpose described above, it may not be removed entirely without destruction of the inwardly directed shoulder 59 at the upper end of the spur gear 45, which is an element of the securing means, or the locking shaft 60, whichever fractures first.

As best shown in FIGURE 3, the size of the clamp top 13 and of a thumb ball clamped thereby are such that as many as three equiangularly spaced thumb balls 11, 69 and 70 may be clamped between the clamping top 13 and the spherical portion 29 of recess 23. The three thumb balls are separated by three identical filler spacers 71, 72 and 73 which fit between the spherical surfaces of the thumb balls and the spherical portion 29 of the recess 23. There is also a central filler 74 configured to the outer surfaces of the thumb balls and journaled on the shaft 60 atop a pair of washers 75 and 76 made of a frictionless material. Only the thumb balls 11 and 70 (the latter in dotted lines) are shown in FIGURE 2, the third thumb ball being above the plane of the figure. It is apparent that there could be only two thumb balls arranged diametrically opposite each other from the axis of the locking shaft 60, in which case there would be only two filler spacers instead of the three spacers 71, 72 and 73, but the two would be of different configuration than those shown in FIGURE 3. Similarly, if there is only one thumb ball, there would be only one filler spacer. The surfaces of the thumb balls, the recesses in the clamping top 13, the surfaces of the filler spacers 71, 72 and 73 and of the central filler 74 are preferably roughened or frosted to prevent relative movement therebetween after being clamped in an adjusted position.

When more than one thumb ball is used, only one is in alignment with the hole 68 in the clamping top 13 and the others (one or two) would be rotated so that 70 their thumb holes 12 are not perpendicular with respect to the surface of the clamping top 13. The purpose of this is to increase the thickness of the material in the clamping top 13 between its outer surface and the surface of a thumb ball so that it will be less susceptible to fracture during actual bowling.

As shown in FIGURE 2, the thumb ball 11 has a flat surface 78 forming a chordal plane that is parallel to the axis of the thumb hole 12. When the thumb ball is not in use, as in the case of the thumb ball 70 of FIGURE 2, it is rotated to a position such that the surface 70A is chordal with respect to the spherical surface of the clamping top 13, and the hemispherical recess in the clamping top 13 has a mating planar surface 70B against which the surface 70A of the thumb ball 70 abuts. Its thumb hole is not indicated. Accordingly, the thickness of the outer wall of the clamping top 13 is thicker than if the thumb ball 70 of FIGURE 2 were completely spherical.

By the construction described above, any one of the thumb balls, from one to three in number, may be aligned with the hole 68 in the clamp top 13. This is accomplished by inserting the wrench 52 and rotating it in a direction to move the locking shaft 60 outwardly until the thumb balls are no longer clamped in position and the clamping top 13 may be rotated to position any one of the three thumb balls in alignment with the hole 68 in the clamp top. Then, when the clamping top is rotated to position the hole 68 in the position where the thumb ball is in the proper position to suit the bowler, and the thumb hole 12 in the thumb ball is also positioned to the satisfaction of the bowler, the wrench 52 is turned in the opposite direction to clamp the thumb ball and clamping top in their selected positions.

The clamping top 16 locates and clamps any one of three middle finger balls 14 in a similar manner, as does the clamping top 19 position any one of three ring finger balls 17, and the construction shown in FIGURE 4 is so similar in most respects to that shown in FIGURE 2 that only the differences will be pointed out.

Referring to FIGURES 1 and 4, one of the ring finger balls 17, having a ring finger hole 18, is shown in FIGURE 1 and in cross section in FIGURE 4. A second one spaced at 120 degrees is shown in dotted lines at 17A in FIGURE 4. Since the normal spread between the middle finger and ring finger is much less than between the middle finger and the thumb, when extended to reach the proper holes in a bowling ball, the middle finger ball 14 and ring finger ball 17 will normally be relatively close, as shown in FIGURE 1, even though their positions are adjustable. It is possible that a bowler may wish to use his little finger instead of his ring finger, in which case the spacing of these finger balls in FIGURE 1 would be farther apart than is shown.

In order to provide for the close spacing of the middle finger ball 14 and the ring finger ball 17 as shown in FIGURE 1 so that their finger holes 15 and 18 may be close together, each of these balls has a substantial portion of their body removed, as best shown by the ring finger ball 17 plan view in FIGURE 5. Although the ball is essentially spherical, it is cut away as shown in FIGURE 5 to a curved outer wall 81 which is essentially the surface of a cylinder having a diameter substantially larger than that of the ball 17 and having an axis substantially but not necessarily parallel to the axis of the middle finger hole 18. The hole through the clamping top 19 for the ring finger hole 18 in the ball 17 is indicated at 82. A ring finger hole ball 17A, is indicated in dotted lines in FIGURE 4, with its ring finger hole 18A, A central filler 83 similar to the filler 74 of FIGURE 3 is used, as well as three equiangularly spaced fillers similar to but differently shaped from the filler spacers 71, 72 and 73 of FIGURE 3. One is shown at 98 in FIGURE 4.

In view of the small space between the middle finger and ring finger balls 14 and 17, there is no room for an O-ring gasket such as 26 in FIGURE 2, and the recesses in the outer surface of the ball 10 to receive the clamping tops 16 and 19 are substantially conical as shown at 84 in FIGURE 4 there being a small gap 85 between the inner surface of the clamping top 19 and the outer surface of the equiangularly spaced filler spacers, so that

when the spur gear 45 is rotated by a wrench 52 there is a wedging action between the clamping top and the conical recess 84 as well as a clamping action against the one or more ring finger balls 17.

As pointed out before, the middle finger ball 14 is adjusted and secured in position in a manner identical to the ring finger ball 17.

The method of construction and assembly of FIGURES 1 to 7 has been expressly shown for the purpose of providing an adjustable bowling ball that will meet the requirements of the American Bowling Congress Bowling Ball Specifications that delineate that any adjustable gripping hole devices must be non-removable to the extent that they must be self-destroying if an attempt is made to remove them from the bowling ball in which they have been initially installed for the purpose of preventing any inadvertent or intentional loading of the ball. Repairs of course must be possible by someone suitably equipped at some later date but not readily during tournament or league play. The bowling ball 10 can also be so constructed by a proper attention to a choice of non-metallic materials and shape and dimensions of the same that the ball can also meet the stringent requirements of the previously mentioned specification as regards to weight and balance.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by Letters Patent is:

1. A substantially spherical bowling ball, having
  - (a) at least two equiangularly spaced inserts in the shapes of segments of a sphere within said ball, each having a finger receiving hole extending substantially axially therethrough, said holes in said inserts being of different diameters,
  - (b) fillers in the assembled ball, one on each side of each insert and each filler in contact with both adjoining inserts and spacing them equiangularly,
  - (c) a circular rotatable clamping top, including a finger receiving hole therethrough, its outer surface being a continuation of the spherical surface of said ball and its inner surface having means engaging each of said inserts, said hole in said clamping top being in alignment with the axial hole in one of said inserts,
  - (d) and securing means within said ball coaxial with said clamping top and operable to secure said inserts and clamping top in a selected position with the hole in one of said inserts in alignment with the hole in said clamping top,
  - (e) said securing means within said ball being accessible from the exterior of said ball through the hole in the clamping top and hole in one of said inserts.
2. The ball described in claim 1, wherein, said securing means comprises:
  - (a) a spur gear having a bore with internal threads,
  - (b) a locking shaft attached to said clamping top and having its inner end threaded for engagement with said internal threads in the bore of said spur gear,
  - (c) and a gear retainer rotatably secured to said ball interiorly of said spur gear and affixed at its outer end to the inner end of said spur gear,
  - (d) said spur gear and gear retainer being rotatable by a wrench inserted through the hole in said clamping top and hole in one of said inserts.
3. The ball described in claim 2, wherein, said securing means is non-removable from said ball without destruction of said securing means.

4. The ball described in claim 2, wherein, all of the elements therein are of non-metallic material.
